UNITED STATES PATENT OFFICE.

HENRY L. BEVERIDGE, OF INDIANAPOLIS, INDIANA.

BOX-BOARD.

No. 925,277.

Specification of Letters Patent.

Patented June 15, 1909.

Application filed March 26, 1908. Serial No. 423,393.

To all whom it may concern:

Be it known that I, HENRY L. BEVERIDGE, of Indianapolis, county of Marion, and State of Indiana, have invented a certain new and 5 useful Box-Board; and I do hereby declare that the following is a full, clear, and exact description thereof, reference being had to the accompanying drawings, in which like numerals refer to like parts.

10 The object of this invention is to provide an improved box board, or board made of paper for use in the manufacture of paper boxes.

The chief feature of this invention consists 15 in a box board formed of a plurality of layers of paper board with reinforcing strips secured between said layers. Heretofore, reinforcing strips have been secured on the inside or the outside of paper boxes at the corners 20 thereof for reinforcing the same. In such case it is troublesome and expensive to add the reinforcing strips to the boxes after they are made and there is left a roughened or angular surface on the box along each edge of 25 the reinforcing strips. With the box board herein set forth the material is all ready for making the box without the subsequent addition of the reinforcing strips, as said strips are already in the box board. After the box 30 is formed the surface of the boxes, both on the inside and the outside, is smooth.

The full nature of this invention will be understood from the accompanying drawings and the following description and claims.

35 In the drawings Figure 1 is a plan view of the sheet of box board with the reinforcing strips indicated by dotted lines. Fig. 2 is a transverse section of the box board on an enlarged scale to show the formation thereof, 40 the same being centrally broken away. Fig. 3 is a transverse section of the box board after the same has been bent, the board being centrally broken away.

In the formation of the box board herein 45 shown three layers 10, 11 and 13 are united by any suitable uniting material, as is well known to manufacturers of box board. The invention need not be limited to board made of three layers, as it may be applied to one having 50 two or more layers.

In the formation of the board longitudinally extending reinforcing strips 15 are inserted between two layers thereof and secured to the adjacent layers by adhesive material in the same manner and at the same 55 time as the other layers are secured together. These reinforcing strips are located at predetermined points where it is intended to score or bend the box board to form the box. In the case of the board herein shown it is 60 bent longitudinally along a score line substantially central of the reinforcing strips 15 and then in forming the box said board is bent at three points to form sides, bottom and top thereof. That is, the portion of the 65 board between the reinforcing strips forms the sides, bottom and top, while the portion outside of said reinforcing strips may form the ends. At any rate, the reinforcing strips are so located between the layers that when 70 the board is folded into a box, the reinforcing strips will overlap the corners. In that herein shown and described, the two reinforcing strips overlap the eight corners of the box 75 that is to be formed. This strengthens and reinforces said corners and yet leaves a box with smooth interior and exterior surfaces and the manufacturer of the boxes is relieved from the expense and trouble of adding reinforcing strips. This renders said box board 80 of great importance in the manufacture of boxes, especially in large quantities.

What I claim as my invention and desire to secure by Letters Patent is:

1. A box board formed of a plurality of 85 layers united together, and reinforcing strips at intervals secured within said layers.

2. A box board formed of a plurality of rectangular layers united together, and a reinforcing strip secured within said layers 90 near each lateral edge of said board where said board will be bent in forming the box.

In witness whereof, I have hereunto affixed my signature in the presence of the witnesses herein named.

HENRY L. BEVERIDGE.

Witnesses:

OLIVE BREEDEN,
